(57) **CLAIM**

The ornamental design for a daylight for an automobile as shown and described.

DESCRIPTION

FIG. 1 is a perspective view of a daylight for an automobile thereof, showing our new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof; and,

FIG. 7 is an enlarge fragmentary perspective view thereof. The relatively lighter foggy toned portions form no part of the claimed design. The broken lines in the figures show no part of the claimed design.
